UNITED STATES PATENT OFFICE.

MONNIE L. EBERHART, OF NEW LISBON, WISCONSIN

HAIR-WAVING DEVICE.

Application filed August 18, 1927. Serial No. 213,791.

My invention has for its object to provide a simple and highly efficient hair waving device, and to this end it consists of the novel devices and combinations of devices herein-
5 after described and defined in the claims.

In the accompanying drawings, which illustrate the invention, like characters indicate like parts throughout the several views.

Referring to the drawings:

10 Fig. 1 is a plan view of the device and also diagrammatically illustrating by means of broken lines the part in the hair and waves on each side thereof;

15 Fig. 2 is a view partly in section taken on the line 2—2 of Fig. 1, and also diagrammatically illustrating said part and waves by means of broken lines and the top of a person's head by means of a single full line;

20 Fig. 3 is a perspective view of one of the spring couplers;

Fig. 4 is a perspective view of one of the coupler anchors and also illustrating by means of broken lines a portion of one of the combs;

25 Fig. 5 is a view in section taken on the line 5—5 of Fig. 4 with the comb shown in full;

Fig. 6 is a plan view showing one form of coupler anchor;

30 Fig. 7 is a front view of the anchor shown in Fig. 6;

Fig. 8 is a view in section taken on the line 8—8 of Fig. 6 and also illustrating a comb to which said anchor is applied;

35 Fig. 9 is a perspective view showing one form of the comb; and

Fig. 10 is a view in section taken on the line 10—10 of Fig. 9 and also fragmentarily illustrating couplers applied thereto.

The letter *a* diagrammatically indicates 40 the outline of a person's head, *b* the part in the hair and *c* waves on each side of the part.

The numeral 11 indicates a plurality of combs commonly called water waving combs. The combs 11 are detachably connected as 45 shown in Figs. 1 and 2 by pairs of yoke-like spring couplers 12 detachably secured by anchors 13 to said combs. The anchors 13 are in the form of loops adapted to rest on the upper surfaces of the backs of the combs 50 11 and are detachably secured thereto by hook-like flanges 13' and Z-shaped lugs 14, said flanges 13' and lugs 14 being integrally formed with the anchors 13. The outer longitudinal edge portions of the combs 11 extend into the flanges 13' and the lugs 14 extend between certain of the teeth of said

combs and engage the inner longitudinal edges of the combs 11 as stops to hold the backs of the combs 11 in the flanges 13'. The outer end portions of the lugs 14 are primarily made straight and then bent after said lugs have been inserted between the teeth of the combs 11.

The couplers 12 are detachably secured to the anchors 13 by hooks 15 formed on the outer end portions of said couplers. By reference to Figs. 1 and 2 it will be noted that the couplers 12 are attached to certain of the anchors 13 by having their hooks 15 inserted through the loops of the respective anchors 13 and over the flanges 13' thereof, and to certain others of said anchors the hooks 15 are attached by simply being inserted over the outer members of the respective anchors 13.

The anchor 16 shown in Figs. 6, 7 and 8 comprises a flat body member adapted to rest on the upper surface of the back of the respective comb 11 and has a hook-like flange 17 and a pair of angle lugs 18. Said flange 17 is adapted to receive the outer longitudinal edge portion of the back of the respective comb 11 and the lugs 18 are adapted to be inserted between certain of the teeth of said combs and engage the inner longitudinal edge portions of said combs as stops. The lugs 18 are primarily made straight and after being inserted between the teeth of the respective comb 11 are bent to shape. The anchor 16 is also provided with a pocket 19 cut and pressed from the stock forming the same. With this type of anchor 16 certain of the couplers 12 are attached thereto by having their hooks 15 applied over the flange 17 and certain other of the hooks 15 are attached to the pocket 19, as illustrated.

Again referring to Figs. 1 and 2, it will be noted that the two combs 11 on each side of the part *c* have their teeth turned toward each other and are connected by a pair of couplers 12 which extend transversely over said combs and their hooks 15 are inserted through anchors 13 and over their flanges 17. Outward of each pair of said combs 11 is a third comb 11 having applied thereto a pair of anchors 13 connected by a pair of couplers 12 to the anchors 13 of the intermediate comb 11. It will be noted that the two couplers 12 connecting the third comb to the intermediate comb extends transversely over said third comb and has certain of their hooks 15 inserted over the longitudinal

edge portions of the loops of the respective anchors 13 and certain other of said hooks are inserted over the inner longitudinal edge portions of the loops of the anchors 13 on the intermediate comb. Fig. 9 shows a specially designed comb 20, the back of which is rolled upon itself and affords a U-shaped ridge 21 having a pair of apertures 22 formed therein. In applying a pair of 10 couplers 12 to this comb, one of the hooks 15 is applied over the ridge 21 and the other thereof is inserted through one of the apertures 22 from the under side of the ridge 21 and interlocked with the back of the comb 20 15 (see Fig. 10). The couplers 12 are common to all of the anchors shown as well as the comb 20. In forming the waves *c*; one of the combs at the part *b* is first placed in position and it is usually called the anchor 20 comb. The hair is then combed to form one of the waves *c* and a second comb is then placed in the hair at the other side of the wave from the first comb, and endwise offset from said first comb. This second comb, 25 while in the wave *c* is moved endwise directly opposite the first comb to cause the hair in the wave to extend obliquely thereof. Two of the couplers 12 are then applied to the two positioned combs, and in so doing 30 said couplers are spread by springing the same, and when released, move the second comb toward the first or anchor comb and thereby cause the combs to securely hold the wave in position. A second wave is then 35 formed and a third comb positioned therein, as shown in Fig. 2, and the second and third combs connected by other of the couplers 12. The waves on the other side of the head are

then formed in a like manner. By providing couplers in the form of arches, they extend over the waves and thereby do not spoil the effect of the wave. 40

What I claim is:

1. In a device of the class defined, the combination with a pair of combs, of a coupler in the form of an arch extending transversely over the combs and attached thereto. 45
2. The structure defined in claim 1 in which said arch is in the form of a spring. 50
3. In a device of the class defined, the combination with a pair of combs, of a pair of laterally spaced couplers in the form of spring arches extending transversely over the combs and removably attached thereto. 55
4. In a device of the class defined, the combination with a pair of combs, of a pair of anchors detachably applied to the combs, and pairs of couplers detachably applied to the anchors, said couplers being in the form of spring arches which extend transversely over the combs. 60
5. The structure defined in claim 4 in which each anchor comprises a body member applicable to one side of the back of the comb and having a hook-like flange engageable with the upper edge of said back and having lugs insertable between the teeth of the comb and secured thereto. 65
6. The structure defined in claim 3 in further combination with a third comb and other couplers in the form of spring arches detachably connecting the second and third combs. 70

In testimony whereof I affix my signature.

MONNIE L. EBERHART.
